[57] **CLAIM**

The ornamental design for a left handed stand torchfoot, as shown and described.

DESCRIPTION

FIG. 1 is a rear right perspective view of a left handed, stand torchfoot showing my new design;
 FIG. 2 is a right side elevational view thereof, the broken line showing of a cutting torch being for illustrative purposes only and forming no part of the claimed design;
 FIG. 3 is a top plan view thereof;
 FIG. 4 is a rear elevational view thereof;
 FIG. 5 is a front elevational view thereof;
 FIG. 6 is a bottom plan view elevational view thereof;
 FIG. 7 is a rear right perspective view of a left handed, stand torchfoot, in a mirror right handed version of FIG. 1 showing my new design;
 FIG. 8 is a right side elevational view thereof based on FIG. 7, the broken line showing of a cutting torch being for illustrative purposes only and forming no part of the claimed design;
 FIG. 9 is a top plan view thereof based on FIG. 7;
 FIG. 10 is a rear elevational view thereof based on FIG. 7;
 FIG. 11 is a front elevational view thereof based on FIG. 7; and.
 FIG. 12 is a bottom plan view elevational view thereof based on FIG. 7.
